UNITED STATES PATENT OFFICE

2,493,136

UMBRELLA

Robert Philip Habig, Bronxville, N. Y.

Application July 3, 1946, Serial No. 681,356

4 Claims. (Cl. 135—20)

1

This invention relates to umbrellas and more particularly to low cost umbrellas which may be discarded after a comparatively short life.

One object of the invention is to provide such an umbrella which though inexpensive in construction will fully protect the user against rain.

Another object of the invention is the provision of an umbrella of this nature which may be made of water-proof or water-repellent paper or other inexpensive material suitable for the purpose.

A further object is to provide such an umbrella with means for keeping same closed when not in use, said means being readily removably maintained from the exterior of the umbrella upon which it is mounted.

Another object is to produce a device of the character described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to denote corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

In carrying out one form of the invention, it was found advantageous to utilize a circular blank of suitable water-repellent or resisting material such as, for instance, paper or the like and score same along lines radiating from the center of the blank so as to adapt same for pleating or folding. It was further found advantageous to score a central circular area and secure thereto an outer and inner disk to form a circular platform from which the umbrella body hinges or pivots, the disks also forming means for securing an umbrella handle upon which there is slidably mounted a sleeve depending from an inner pleated circular blank secured to the outer blank or body and forming means for operating the umbrella for opening and closing.

In the drawings:

Figure 1 is a perspective view of the umbrella in open position;

2

Figure 2 is a perspective view of same when closed;

Figure 3 is a bottom plan view thereof in open position;

5 Figure 4 is a fragmental sectional view at an enlarged scale of the upper portion of the umbrella shown in Figure 1;

Figure 5 is a similar view to Figure 4 but taken at a point below the top;

10 Figure 6 is a face view of the outer or body forming blank; and

Figure 7 is a fragmental face view of the central portion of the body blank at an enlarged scale.

15 Referring now to the drawings in detail, the numeral 10 indicates an umbrella made in accordance with the present invention. The said umbrella comprises an outer covering or body portion 11 made from a preferably circular blank 12 of water-proof or water-repellent stiff strong paper or similar material.

In forming the umbrella cover 11, the blank 12 is scored along radial lines 13 emanating from the center of the blank and extending to the

25 periphery thereof. The blank may be of any suitable diameter ranging from approximately thirty inches upward. Besides the radial score lines, there is provided a circular score line 14 at the center of the blank of about two inches

30 in diameter, the said circular score line forming an umbrella hinge as will hereafter be described. The radial score lines 13 make it possible for

35 folding or forming pleats 15 in the cover portion 11. To further facilitate the formation of

the said pleats, the central portion of the blank enclosed in the circular score 14 may be slit or cut in V formations as shown at 16 in Figure 7.

The portion within the central circular score 14 forms a platform 17 to the exterior of which

40 is glued or pasted a circular disk 18 and to the underside of which a similar disk 19 is similarly secured. The lower disk 19 may be centrally perforated to receive one end of the tubular rod 20, the said end may be slit so as to form

45 bent over tabs 21 pasted or otherwise secured to and between the said disks 18 and 19.

An inner pleated circular web 22 of a diameter somewhat smaller than the body or cover 11 is

50 stapled or otherwise secured at 23 to the underside of the cover 11 and is provided with a central portion similar to that shown at 16, Figure 7, but which is bent down to form a hollow hub 24 (see Fig. 5) which embraces and is secured to

55 the upper end of a sleeve 25 slidable on the hollow rod 20 which may be made of cardboard or

other suitable material. The handle end 26 of the tubular rod 28 may be provided with a looped cord 27 for carrying the umbrella.

In practice, when it is desired to open the umbrella, a hoop or ring 28 (see Fig. 2) which normally keeps the umbrella closed, is removed and the sleeve 25 is drawn downwardly with one hand while the handle is held with the other. This action causes the body 11 through the connecting web 22 to spread out and open up on its circular hinge 14. The sleeve is pulled down until the umbrella is fully open and held against the rod 20 by pressure of the fingers or tied thereagainst. To close the umbrella the process is reversed, that is, the sleeve 25 is slid upward until the umbrella is fully folded and then the hoop 28 is slipped thereon.

From the foregoing it will be seen that the umbrella of the present invention is of simple inexpensive construction and provides for a limited time all the benefits or protection of the more expensive umbrellas and one which on account of its inexpensiveness may be discarded after a single use, if so desired. It is to be understood, however, that such need not be the case, as the umbrella may be used repeatedly for quite a number of times before its usefulness is at an end.

What is claimed is:

1. An umbrella comprising a radially pleated water-resistant outer covering made of relatively fibrous material, an inner pleated web secured at its periphery to the said outer covering, a rod, radially disposed tabs at one end of said rod and connecting the same to said covering, a hinge on the covering, and a sleeve slidable on the rod secured to the center of the web.

2. An umbrella comprising an outer covering made from a circular blank of a water resistant relatively heavy fibrous material having radial score lines extending from the center to the periphery thereof, V shaped radial pleats formed between said score lines, a central circular score line forming a hinge on said outer covering, an upper and a lower disk secured to said covering within the circumference of said circular score line, a rod centrally secured to said disks, an inner circular web similarly scored and pleated as the outer covering secured near its periphery to

the said outer covering, and a sleeve extending outwardly from said web slidably mounted on said rod for opening and closing said umbrella.

3. An umbrella comprising an outer covering made from a circular blank of a water resistant relatively heavy fibrous material having radial score lines extending from the center to the periphery thereof, V shaped radial pleats formed between said score lines, a central circular score line forming a hinge on said outer covering, an upper and a lower disk secured to said covering within the circumference of said circular score line, a rod, radially disposed means on one end of said rod and secured between said disks; an inner circular web similarly scored and pleated as the outer covering secured near its periphery to the said outer covering, and a sleeve extending outwardly from said web slidably mounted on said rod for opening and closing said umbrella.

4. An umbrella of the nature described comprising an outer circular body and an inner circular web of lesser diameter than the outer body secured near its periphery to the said body, both the outer body and inner web having radial pleats extending from their respective centers to their circumferences, a reinforced area at the center of said body, a circular hinge formed on the outer body about said reinforced area, a rod, radially disposed tabs at one end of said rod and connected to said reinforced area, and a sleeve on said web slidable on said rod as and for the purpose specified.

ROBERT PHILIP HABIG.
